United States Patent Office.

FRANZ LEHMANN, OF RIVERSIDE, ILLINOIS.

Letters Patent No. 96,928, dated November 16, 1869.

IMPROVEMENT IN HORSE-SHOERS' HOOF-PARER.

The Schedule referred to in these Letters Patent and making part of the same.

I, FRANZ LEHMANN, of Riverside, in the county of Cook, and State of Illinois, have invented certain Improvements in Horse-Shoers' Hoof-Parers, of which the following is a specification.

My invention relates to a novel knife, to be used as a farrier's tool to pare away the hoofs of a horse, preparatory to shoeing him.

It consists in providing a novel-shaped blade, with a curved handle, both of which will be more fully hereinafter described.

Description of the Accompanying Drawing.

Figure 1 is a side view of the tool.

Figure 2 is a front view of the same.

General Description.

A is a steel blade, having its sides turned up, as at *a a*.

The cutting-edge is along the front of the blade and the front of the upturned sides.

The blade A is slightly curved from side to side, the line of curvature being shown in fig. 2, so that the centre of the cutting-edge is slightly lower than the sides of the same.

Attached to the back of this blade is the metallic shank B, curved so that it overhangs the cutting-edge of the blade.

To an elongated portion of this shank are riveted

the handle-pieces C C, the same being of bone, wood, horn, or like material. I use horn.

The entire handle may be made of metal, but I prefer, for the sake of lightness, to rivet the pieces C C, of horn or other light material, to the shank, as above described.

The advantage of this invention over the ordinary farriers' knife, which generally consists of a simple blade, bent at the end, is, that it enables the workman to have a better grasp and purchase to his tool, thereby saving much expenditure of muscle, and, at the same time, offers, by its sharp corners and upturned sides, a superior cutting-edge with which to pare close up to the frog of the hoof, or the edge of the shoe, without injuring the hoof.

Owing to the curvature given the handle, the weight of the workman's hand is put to its best advantage.

Claim.

I claim, as my invention—

The horse-shoers' hoof-parer, composed of the blade A *a* and the handle, constructed substantially as and for the purpose specified.

FRANZ LEHMANN.
